Brayton B. Chittenden of Dingbushen, New York

1100 - Patent.

He has agreed to the Letting Party, and making
part of the same, containing a copy of the words of the
said George W. Blunt, showing of his improvement in the
portable reflecting telescope.

50
This I claim as new is just the heat con-shape of the Baker, being the best calculator to concentrate the heat radiating from the cylinder upon the water to be heated, 2nd the movable reflector and 3rd the construction and position of the cylinder, the operation is performed by placing the water to be heated on plates and placing the latter on the rods on the reflectors adjusted as in fig. 2 and two coils placed in the reflector the operation is thus performed sooner than in any known oven or Baker, with an immense saving of fuel!
